CLAIM

The ornamental design for a media streaming accessory, as shown and described.

DESCRIPTION

FIG. 1 is a front perspective view of a media streaming accessory showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The break lines shown in FIGS. 1–5 indicate a symbolic break in length. The appearance of any portion of the media streaming accessory on or between the break lines forms no part of the claimed design.

1 Claim, 5 Drawing Sheets

Related U.S. Application Data

a continuation of application No. 29/824,141, filed on Jan. 21, 2022, now Pat. No. Des. 952,629, which is a continuation of application No. 29/737,185, filed on Jun. 5, 2020, now Pat. No. Des. 945,416.
